SHOULDER PAD

Anne Ingalls, Chicago, Ill.

Application January 12, 1946; Serial No. 640,740

7 Claims. (Cl. 2—268)

1

This invention relates to shoulder pads, and it has particular reference to shoulder pads designed for wear by women on their shoulders for the purpose of accentuating their shoulder lines.

The main objects of the invention are to provide a shoulder pad of the character indicated, which may be quickly and easily associated with the shoulder straps of other garments for positioning the parts on the wearer's shoulder; to provide a shoulder pad construction which will facilitate laundering thereof, and, in general, it is the object of the invention to provide a convenient and practicable shoulder pad construction of the character indicated.

Other objects and advantages will be understood by reference to the following specification and accompanying drawing wherein there is illustrated a selected form of shoulder pad construction embodying the invention.

In the drawing,

Fig. 1 is a perspective illustrating the application of the shoulder pads to the wearer;

Fig. 2 is a plan view of the under side of the pad;

Fig. 3 is a cross section on the line 3—3 of Fig. 2 but showing the pad as it would appear when conformed to the shoulders of a wearer;

Fig. 4 is a section on the line 4—4 of Fig. 3;

Figs. 5, 6 and 7 are illustrations showing the patterns of the elements employed in forming the shoulder pad envelope and

Fig. 8 is a section corresponding to Fig. 3 but showing a modified arrangement.

The shoulder pad construction shown in the drawing consists of a washable textile fabric envelope embodying top and bottom fabric members 1 and 2, which are connected at their outer edges by means of an edge strip 3. The edge strip 3 is stitched at its longitudinal edges to adjacent edges of the top and bottom members 1 and 2 as indicated at 4 and 5 respectively.

As shown in Fig. 6, the bottom member 2 is initially of generally semi-circular form although the rounded outer edge portion 6 is actually of oval contour rather than circular. For convenience, the rounded outer edge may be referred to as either semi-circular or oval. The opposite, inner marginal edge portion 7 of the bottom member 2 embodies a straight inner edge 8.

The top member 1 has an outer rounded edge 9 which corresponds to the rounded edge 6 of the lower member and the inner portion thereof presents a substantially rectangular section having a straight inner edge 10 and approximately square cut end edges 11—11, the outer ends of

which are joined to the rounded edge of the inner portion by means of substantially straight inner edge portions 12—12.

The edge strip 3 is an elongated narrow strip having its widest transverse dimension approximately midway between its ends and gradually tapered towards its ends as shown. When the strip 3 has its opposite arcuate edges 13—13 united to the edges 8 and 6 of the top and bottom members 1 and 2 respectively, the result will be an envelope which is adapted to be distended to present a wedge-shaped cross section substantially as illustrated in Fig. 3.

The inner rectangular portion of the top member 1 is adapted to be folded upon itself about a line, such as represented at 14, which is approximately midway between the edges 10 and 12 thereby producing a flap portion 15 (Fig. 3) which underlies the inner marginal portion 16 of the bottom member 2. The stitching 5 which unites the rounded inner edge of the member 2 to one of the edges of the edge strip 3 terminates as indicated at 17 at the free edge 8 of the said marginal portion 16, and said free edge remains unattached to the overlying portion of the top member 1 so as to constitute an opening affording access to the interior of the pocket thus formed. Any suitable padding or wadding material 18 may be introduced into or removed from the envelope through said opening, the flap 15 being of course suitably unfolded.

The end portions of the flap 15 project endwise beyond the normal end edges of the pad body as clearly shown and the inner edge portions of these end projections are stitched or otherwise united as indicated at 19 to the overlying inner edge portions 12 of corresponding endwise projecting end portions of the top member 1. Stitching or other suitable means, such as indicated at 20, also is preferably provided for uniting the end edges of the flap projections and the overlying projections of the top member 1.

At about the middle of the flap 15, that is, centrally of its ends, it is provided with a snap fastener element 21 which is adapted to engage a cooperating snap fastener element 22 carried by the shoulder strap 23 of a woman's garment. At the ends of the endwise projections above referred to, there are provided straps or loop elements 24—24 which are preferably stitched or otherwise permanently attached at one end as indicated at 25, to an edge of the projections and provided with snap fastener means as indicated at 26 for detachably connecting them to the end projections near their inner edges. The loop straps 24

are adapted to cooperate with the overlying portions of the shoulder pad to form loops for slidably receiving the shoulder strap 23.

By providing the endwise extensions at the inner side portions of the pad with their shoulder strap receiving loops, the shoulder straps are enabled to easily pull the opposite ends of the shoulder pad downwardly to thereby conform the shoulder pad substantially to the shoulders of the wearer. The lengthened inner marginal portion thus provided overcomes the normal resistance to such conformation which is generally experienced with shoulder pads and the wedge shaped form cooperates with this elongation to facilitate the transmission of such conforming curvature of the inner portions of the pads to the outer portions without an abrupt change. The rounded outer edge shape likewise cooperates with the inner margin elongation and transverse wedge shape to facilitate shoulder conformation of the pad without any prominent, abrupt changes in the shape of the shoulder pad.

When the shoulder pad is to be applied, the snap fasteners 26 of the loops are disengaged so that the shoulder strap can be placed inside of the loop straps whereupon the fasteners 26 are engaged to thereby retain the shoulder pad in overlying relation to the shoulder strap. To prevent the pad from sliding longitudinally along the shoulder strap, the snap fastener 21 is engaged with the shoulder strap carried fastener element 22 which may be so located on the shoulder strap as to position the pad in the desired location.

In a modified arrangement represented in Fig. 8, the free marginal edge portion 16a of the under member 2 of the pad envelope is extended into proximity to the line of fold of the flap portion 15 relative to the overlying portion of the top member 1. The end loops 24 are omitted and the flap 15 is provided at its ends with snap fasteners, such as represented at 27 for detachably holding the flap 15 in its closed position. The marginal portion 16a is provided with a snap fastener element 21a (corresponding to the fastener element 21) for cooperating with the snap fastener element 22 carried by the shoulder strap 23. In this arrangement the shoulder strap is positioned between the flap 15 and the marginal portion 16a of the bottom member 2 of the pad, and the pad is held against movement longitudinally of the shoulder straps by inter-engagement of the snap fastener elements 21a and 22. If desired, additional snap fasteners, such as indicated at 28, may be provided along the free edge of the flap 15 to hold the same in closed position although this is not ordinarily necessary since, when the shoulder pad is worn, it is normally held in closed position by being confined between the shoulder of the wearer and the overlying portion of the pad.

It will be seen that the pad structure described may be quickly and easily applied to or removed from the shoulder strap of any garment, and that it may be interchangeably associated with any number of different garment shoulder straps. The washable textile fabric envelope may be emptied of its wadding for laundering purposes and the wadding quickly and easily replaced with the same or with fresh wadding whenever desired. Thus the laundering of the shoulder pad is greatly facilitated in that it is not required that the hard-to-dry wadding material be laundered each time that the fabric cover is so treated.

While any suitable form of wadding, such as

cotton, kapok, or the like, may be employed for filling the envelope and distending it to the desired wedge or other predetermined shape, supplies of such material are not always conveniently available. However, it has been found that it is quite practicable to employ any conventional sanitary napkin for filling purposes, such napkins being susceptible of compression and reshaping as may be required for pad filling purposes. Since various padding materials mentioned are very inexpensive, it is entirely practicable that when laundering the structure, to merely launder the fabric envelope and to refill it with new and fresh padding which may, if desired, be suitably scented.

If desired, the shoulder pad may be worn with the pocket closing flap on the upper side, the shoulder strap being attached by a snap or other suitable fastener to the then bottom of the envelope. When so arranged, there is an automatic tendency for the flap to be held tightly closed.

Various changes in the structure may be made without departing from the invention.

I claim:

- 25 1. A shoulder pad of the class described, comprising a flexible material envelope embodying top and bottom walls having outer and end edges secured together, said bottom wall having an inner edge adjacent the inner edge of the pad and free of attachment to said top wall to form an opening affording access to the inside of the envelope, the top wall having an inner edge flap extension folded to underlie the inner marginal portion of said bottom wall to close said access opening, the pad being tapered in thickness from its outer edge toward its inner edge and said access opening, and means carried by said flap for interconnecting the pad and a shoulder strap of a garment to thereby position the pad.
- 30 2. A shoulder pad of the class described, comprising a flexible material envelope embodying top and bottom walls having outer and end edges secured together, said bottom wall having an inner edge adjacent the inner edge of the pad and free of attachment to said top wall to form an opening affording access to the inside of the envelope, the top wall having an inner edge flap extension folded to underlie the inner marginal portion of said bottom wall to close said access opening, and loops carried by said flap adjacent its ends for receiving the shoulder strap of a garment to thereby position the pad and cause its conformation to the wearer's shoulder, said loops each having one end detachably connected to said flap so as to facilitate insertion of said shoulder strap between said loops and said flap.
- 35 3. A shoulder pad of the class described, comprising a flexible material envelope embodying top and bottom walls having outer and end edges secured together, said bottom wall having an inner edge adjacent the inner edge of the pad and free of attachment to said top wall to form an opening affording access to the inside of the envelope, the top wall having an inner edge flap extension folded to underlie the inner marginal portion of said bottom wall to close said access opening, loops carried by said flap adjacent its ends for slidably receiving the shoulder strap of a garment to thereby position the pad and cause its conformation to the front to back curvature of the wearer's shoulder, and means for anchoring the pad to such shoulder strap against sliding movement longitudinally thereof.
- 40 4. A shoulder pad of the class described, comprising a flexible material envelope embodying top and bottom walls having outer and end edges secured together, said bottom wall having an inner edge adjacent the inner edge of the pad and free of attachment to said top wall to form an opening affording access to the inside of the envelope, the top wall having an inner edge flap extension folded to underlie the inner marginal portion of said bottom wall to close said access opening, loops carried by said flap adjacent its ends for receiving the shoulder strap of a garment to thereby position the pad and cause its conformation to the front to back curvature of the wearer's shoulder, and means for anchoring the pad to such shoulder strap against sliding movement longitudinally thereof.
- 45 5. A shoulder pad of the class described, comprising a flexible material envelope embodying top and bottom walls having outer and end edges secured together, said bottom wall having an inner edge adjacent the inner edge of the pad and free of attachment to said top wall to form an opening affording access to the inside of the envelope, the top wall having an inner edge flap extension folded to underlie the inner marginal portion of said bottom wall to close said access opening, loops carried by said flap adjacent its ends for receiving the shoulder strap of a garment to thereby position the pad and cause its conformation to the front to back curvature of the wearer's shoulder, and means for anchoring the pad to such shoulder strap against sliding movement longitudinally thereof.
- 50 6. A shoulder pad of the class described, comprising a flexible material envelope embodying top and bottom walls having outer and end edges secured together, said bottom wall having an inner edge adjacent the inner edge of the pad and free of attachment to said top wall to form an opening affording access to the inside of the envelope, the top wall having an inner edge flap extension folded to underlie the inner marginal portion of said bottom wall to close said access opening, loops carried by said flap adjacent its ends for receiving the shoulder strap of a garment to thereby position the pad and cause its conformation to the front to back curvature of the wearer's shoulder, and means for anchoring the pad to such shoulder strap against sliding movement longitudinally thereof.
- 55 7. A shoulder pad of the class described, comprising a flexible material envelope embodying top and bottom walls having outer and end edges secured together, said bottom wall having an inner edge adjacent the inner edge of the pad and free of attachment to said top wall to form an opening affording access to the inside of the envelope, the top wall having an inner edge flap extension folded to underlie the inner marginal portion of said bottom wall to close said access opening, loops carried by said flap adjacent its ends for slidably receiving the shoulder strap of a garment to thereby position the pad and cause its conformation to the front to back curvature of the wearer's shoulder, and means for anchoring the pad to such shoulder strap against sliding movement longitudinally thereof.
- 60 8. A shoulder pad of the class described, comprising a flexible material envelope embodying top and bottom walls having outer and end edges secured together, said bottom wall having an inner edge adjacent the inner edge of the pad and free of attachment to said top wall to form an opening affording access to the inside of the envelope, the top wall having an inner edge flap extension folded to underlie the inner marginal portion of said bottom wall to close said access opening, loops carried by said flap adjacent its ends for receiving the shoulder strap of a garment to thereby position the pad and cause its conformation to the front to back curvature of the wearer's shoulder, and means for anchoring the pad to such shoulder strap against sliding movement longitudinally thereof.
- 65 9. A shoulder pad of the class described, comprising a flexible material envelope embodying top and bottom walls having outer and end edges secured together, said bottom wall having an inner edge adjacent the inner edge of the pad and free of attachment to said top wall to form an opening affording access to the inside of the envelope, the top wall having an inner edge flap extension folded to underlie the inner marginal portion of said bottom wall to close said access opening, loops carried by said flap adjacent its ends for receiving the shoulder strap of a garment to thereby position the pad and cause its conformation to the front to back curvature of the wearer's shoulder, and means for anchoring the pad to such shoulder strap against sliding movement longitudinally thereof.
- 70 10. A shoulder pad of the class described, comprising a flexible material envelope embodying top and bottom walls having outer and end edges secured together, said bottom wall having an inner edge adjacent the inner edge of the pad and free of attachment to said top wall to form an opening affording access to the inside of the envelope, the top wall having an inner edge flap extension folded to underlie the inner marginal portion of said bottom wall to close said access opening, loops carried by said flap adjacent its ends for receiving the shoulder strap of a garment to thereby position the pad and cause its conformation to the front to back curvature of the wearer's shoulder, and means for anchoring the pad to such shoulder strap against sliding movement longitudinally thereof.
- 75 11. A shoulder pad of the class described, comprising a flexible material envelope embodying top and bottom walls having outer and end edges secured together, said bottom wall having an inner edge adjacent the inner edge of the pad and free of attachment to said top wall to form an opening affording access to the inside of the envelope, the top wall having an inner edge flap extension folded to underlie the inner marginal portion of said bottom wall to close said access opening, loops carried by said flap adjacent its ends for receiving the shoulder strap of a garment to thereby position the pad and cause its conformation to the front to back curvature of the wearer's shoulder, and means for anchoring the pad to such shoulder strap against sliding movement longitudinally thereof.

and bottom walls having outer and end edges secured together, said bottom wall having an inner edge adjacent the inner edge of the pad and free of attachment to said top wall to form an opening affording access to the inside of the envelope, the top wall having an inner edge flap extension folded to underlie the inner marginal portion of said bottom wall to close said access opening, said flap extension and the overlying portion of said top wall having end portions projecting endwise of the pad beyond its normal end edges, said endwise projecting flap and top wall portions being united adjacent their outer and inner edges, and loops secured to the under sides of said endwise projections for receiving the shoulder strap of a garment to thereby position the pad and cause its conformation to the wearer's shoulder.

5. A shoulder pad of the class described, comprising a flexible material envelope embodying top and bottom walls having outer and end edges secured together, said bottom wall having an inner edge adjacent the inner edge of the pad and free of attachment to said top wall to form an opening affording access to the inside of the envelope, the top wall having an inner edge flap extension folded to underlie the inner marginal portion of said bottom wall to close said access opening, said flap cooperating with the overlying portion of the envelope to provide a shoulder strap receiving tube for positioning the pad, and means for securing said flap in closed position with said shoulder strap enclosed in said tube.

6. A shoulder pad of the class described, comprising a flexible material envelope embodying top and bottom walls having outer and end edges secured together, said bottom wall having an inner edge adjacent the inner edge of the pad and free of attachment to said top wall to form an opening affording access to the inside of the envelope, the top wall having an inner edge flap

extension folded to underlie the inner marginal portion of said bottom wall to close said access opening, said flap cooperating with the overlying portion of the envelope to provide a shoulder strap receiving tube for positioning the pad, and means for anchoring the pad to such shoulder strap against movement longitudinally of the strap, and means for securing said flap in closed position with said shoulder strap enclosed in said tube.

10 7. A shoulder pad of the class described having inner and outer side edges and front and rear ends, the pad tapering in thickness from its outer side edge toward its inner edge, extensions projecting from the front and rear ends of the pad, and means carried by said extensions adjacent their free ends for slidably anchoring said extension ends to forwardly and rearwardly spaced portions of a garment shoulder strap which extends over the shoulder of the wearer of the shoulder pad, whereby to effect conformation of the pad to the front to back curvature of the wearer's shoulder, and means for securing the pad to said shoulder strap against movement lengthwise of the strap.
